UNITED STATES PATENT OFFICE.

FRED E. WHITE AND ALFRED RUTTIMAN, OF GARDNER, MASSACHUSETTS, ASSIGNEES
TO FLORENCE STOVE COMPANY, OF GARDNER, MASSACHUSETTS, A CORPORATION
OF MASSACHUSETTS.

AUTOMATIC BURNER ADJUSTMENT.

Application filed June 3, 1926. Serial No. 113,519.

The present invention relates to means for insuring the proper adjustment of a burner of a constant level oil stove.

In stoves of this type a constant level of fuel oil is supplied and the wick or kindler of the burners is lowered or raised below or above this oil level as it is desired to light or extinguish the same.

The relation of the oil level to the burner for lighting purposes is usually such that after lighting the flame must be turned down for cooking, that is the burner must be raised somewhat in relation to the oil level. This is especially true after the stove has been burning for some time and the oil in the supply line has become heated and its specific gravity consequently decreased which may result in flooding the oil bowl which supports the burners.

10 The invention particularly concerns means for automatically insuring the burner being adjusted from the lighting to burning position without thought on the part of the housewife or operator so that flooding or smoking will be prevented. At the same time the burner may be manually adjusted between high and low burning limits and may be extinguished without interference with the above mentioned automatic operation or mechanism.

Specifically the invention consists of an automatic adjusting device of the type described which when brought manually into lighting or ignition position will spring back to the burning position when the handle is released thereby insuring normal and safe operation of the stove.

A stove of this type is illustrated in a patent to White No. 1,488,854 in which a suitable burner elevating mechanism is also shown. No claim is made in this application to any specific form of burner or burner elevating mechanism.

We have illustrated in the accompanying drawings a preferred form of our invention in which

Fig. 1 is a front view of handle and dial plate.

Fig. 2 is a sectional elevation along the line 2—2 of Fig. 1

Fig. 3 is a view partly in section of the device of Fig. 2 with certain parts removed

and with the torsion spring in "Burning" position.

Fig. 4 is a view similar to Fig. 3 with the torsion spring approaching "Ignition" position.

Fig. 5 is a view similar to Fig. 3 with the torsion spring in "Ignition" position.

Fig. 6 is a perspective view of the torsion spring.

Referring now with particularity to the form shown in the drawings, the numeral indicates a spindle capable of rotation as in Patent No. 1,488,854 to elevate and lower a 65 burner in the usual manner. An angular extension 2 of the spindle is attached as by means of bolt 3 to a handle gear 4 provided with a handle 5 and a pointer 6.

The spindle 1 is rotatable in bearing boss 70 secured to a dial plate 8, which is provided with certain designations such as "Out", "Burn here" and "Light."

Surrounding the bearing boss 7 is a torsion spring 9 which is held within a split 75 tubular extension 10 of the handle gear 4. Each end of the torsion spring 9 is bent outwardly as at 11 and 12 and these ends lie in the split portion of the tubular extension 10.

80 A stationary boss 13 is secured to the dial plate by any desired means so that upon rotation of the handle gear 4, one end 11 of the spring 9 will engage the same.

The spring 9 is initially put under a tension substantially equivalent to or somewhat greater than the friction to be overcome in raising and lowering the burner and assembly by rotation of the spindle 1. It will be noted that the spring is inactive and rotates freely so long as the burner gear 4 is operated between the "Burn here" and the "Out" positions. In other words the handle gear may be manually set at any point between these limits without interference with or by the spring mechanism. If, however, the handle gear is turned to the left beyond the "Burn here" position, the end 11 engages the boss 13 and the spring is torsioned to an extent that when the handle is released the spindle and handle will be automatically brought back to the "Burn here" position which is the safe position and level for usual operation of the stove.

It will also be seen from Fig. 5 that the handle cannot be turned beyond the "Light here" position as one edge of the split of the tubular member engages the end 11 of the 5 spring 9 which is already held against further movement by the boss 13.

It is to be understood that the "Out", "Burn here" and "Light" indications on dial plate correspond to positions of the burner with relation to the oil level so that the 10 respective actions will or may take place.

We claim:

1. In combination, a rotatably mounted burner moving spindle, manually operated 15 means for rotating said spindle through an arc, and spring means for retractably rotating said spindle through a portion of said arc only.
2. In combination, a rotatably mounted 20 burner moving spindle, manually operated means for rotating said spindle through an arc, including a split tubular member movable with said spindle and a spring within said member freely movable through a portion 25 of said arc and a stationary stop engageable by said spring at the end of said arc, said spring resisting movement through the remainder of said arc.
3. In combination, a rotatably mounted

burner moving spindle, manually operated 30 means for moving said spindle through an arc and automatic means for retractably rotating said spindle through a portion of said arc including a spring surrounding said spindle freely rotatable through a portion 35 of said arc, and a stationary stop engageable by said spring at the end of said arc, said spring resisting movement of said manually operated means through the remainder of 40 said arc.

4. In combination, a rotatably mounted burner elevating spindle, a bearing therefor, a manually operated handle attached to said spindle, having a split tubular extension surrounding said bearing but spaced therefrom, a spring between the bearing and the tubular extension, the ends of said 45 spring lying in the split of the tubular extension and a stationary boss in the path of rotation of one of the spring ends, whereby 50 when the handle is rotated beyond a predetermined point, the spring end will engage the boss and the spring will resist further movement of the handle.

In testimony whereof we affix our signatures.

FRED E. WHITE.
ALFRED RUTTIMAN.
